(57) **CLAIM**

We claim the ornamental design for a cellular telephone, as shown.

DESCRIPTION

FIG. 1 is a front perspective view of the cellular telephone of the present invention;

FIG. 2 is a front elevation view of the cellular telephone of the present invention;

FIG. 3 is a rear elevation view of the cellular telephone of the present invention;

FIG. 4 is a first side view of the cellular telephone of the present invention;

FIG. 5 is a second side view of the cellular telephone of the present invention;

FIG. 6 is a top plan view of the cellular telephone of the present invention;

FIG. 7 is a bottom plan view of the cellular telephone of the present invention; and,

FIG. 8 is a front elevation view, in an unfolded state, of the cellular telephone of the present invention.
